PUMP ROD ASSEMBLY

Charles Isaac Leibensperger, Columbus, Ohio
Application March 20, 1952, Serial No. 277,675

4 Claims. (Cl. 255—28)

My invention relates generally to pump rods and couplings and more particularly to a flexible pump rod assembly adapted to conform to a gradual curvature in a well pipe.

An object of this invention is to provide a pump rod assembly wherein a simple, inexpensive coupling is utilized to join rod segments made from standard mill stock lumber of rectangular cross section.

Another object of this invention is to join alternate rod segments at ninety degrees to each other, with respect to their rectangular cross sections, by means of a novel coupling. The result is to affect a minimum of clearance between the rod and the pipe well, thereby reducing the tendency in the rods to buckle. At the same time, by placing the alternate rod segments at ninety degrees to each other, with respect to their rectangular cross sections, some flexibility is maintained wherein the rods may conform to a gradual curvature in a well pipe.

Further objects and advantages of the present invention will be apparent from the following description, reference being had to the accompanying drawings wherein preferred forms of embodiments of the invention are clearly shown.

In the drawings:

Fig. 1 is a side view, partially in elevation and partially in section, showing pump rod segments and a coupling constructed in accordance with the present invention;

Fig. 2 is a sectional view taken along the line 2—2 of Fig. 1 and showing the coupling and pump rod segments of the present invention;

Fig. 3 is a partial perspective view of the present invention;

Fig. 4 is a side view, partially in elevation and partially in section, showing another coupling embodiment constructed in accordance with the present invention;

Fig. 5 is a partial perspective view of the coupling of Fig. 4; and

Fig. 6 is a side view, partially in elevation and partially in section, of a well showing the installation of a pump rod assembly formed in accordance with the present invention.

Fig. 7 is a side view showing still another coupling embodiment constructed in accordance with the present invention.

Referring to the drawing and more particularly to Fig. 1, a drop pipe 10, such as is used in wells to encase pump rod assemblies, is shown. Within the drop pipe 10, pump rod segments 11 and 12 are shown joined so that such alternate rods 11 and 12 are at ninety degrees to each other with respect to their rectangular cross sections. The pump rod segments 11 and 12 are preferably made from standard mill stock lumber of rectangular cross section and of a standard length. These two pump rod segments are joined by means of two metal straps 13 and 14, with each of said straps having a ninety degree twist at its center. Both the straps 13 and 14 are identical. For convenience of description the details of strap 14 will be

2

described and indicated on the drawing. Strap 14, Fig. 1, has an upper plane portion indicated at 15 and a lower plane portion indicated at 16. These plane portions are provided with protruding portions 17 which extend into recesses countersunk in the wood pump rod segments to provide additional bearing area for the metal coupling straps relative to the wood pump rod segments. These protrusions 17 are preferably integrally formed in the plane portions of the coupling straps by stamping, and are provided with holes 19 for receiving the bolts 20. The nuts 21 cooperate with the bolts 20 to secure the metal coupling straps to the ends of the pump rod segments in lap joined relation. In Fig. 3 the same coupling shown in Fig. 1 is pictured in perspective to more clearly illustrate the ninety degree twist that is formed in each metal coupling strap.

In Fig. 4 a drop pipe 30, such as is commonly used in wells for enclosing the pump rod assembly, is shown. Pump rod segments 31 and 32 are shown encased in the drop pipe 30. This particular embodiment utilizes a different coupling structure indicated generally at 33. A metal block 34 is provided with a male threaded portion 35 formed thereon. A second metal block 36 is provided with a female threaded portion 37 formed therein. The metal block 34 is joined to the pump rod segment 31 by means of two metal straps 38 and 39 and the metal block 36 is joined to the lower pump rod segment 32 by the two metal straps 41 and 42. All of the metal straps are identical, and each is provided with integrally formed protrusions 43 which serve as additional bearing surfaces between the metal straps and the metal blocks 34 and 36 and between the metal straps and the pump rod segments 31 and 32 to which such metal straps are lap joined. The metal blocks 34 and 36 are provided with countersinks 45 for receiving the projecting bearing sections 43 of the straps. Likewise, the pump rod segments 31 and 32 are provided with countersinks 46 for receiving the protruding bearing portions 43 of the metal straps. To lap join the metal blocks to the pump rod segments, bolts 48 and nuts 49 are provided. The shanks of such bolts are passed through holes 50 in the metal strap and through holes 51 in the blocks and through holes 52 in the pump rod segments.

The threaded type coupling 33, shown in Figs. 4 and 5, is constructed so that when the threaded portions 35 and 37 are engaged and tightened, the pump rod segments 31 and 32 will be maintained in a joined relationship such that the alternate rods are at substantially ninety degrees to each other with respect to their rectangular cross sections.

Fig. 7 shows an additional embodiment of the same invention. This embodiment is similar to the twisted strap coupling first described but differs from it in that only one such strap is used. When a single strap type coupling is used, such strap is formed from heavier metal than that used in the double strap coupling previously described. In this latter embodiment pump rod segments 61 and 62 are joined by a single twisted strap 63. Such strap is lap joined to the respective pump rod segments by the bolts 64 and the nuts 65 which are passed through holes 66 in the pump rod segments and holes 67 in the coupling strap. Here again, as in the previous embodiment, the metal straps are provided with projecting bearing portions 68 which are preferably stamped into the strap. Bearing washers 69 are countersunk into the pump rod segments to add additional bearing surface between the bolt 64 and the wooden pump rod segments as is seen in Fig. 7. The twisted coupling strap 63 serves to maintain the alternate pump rod segments 61 and 62 at substantially ninety degrees to each other with respect to their rectangular cross sections.

Fig. 6 shows a typical water well 70 sunk into the earth which is indicated generally at 71. It should be noted that this well is shown to have a gradual curvature such as frequently results in the sinking of water wells. A pump jack, indicated generally at 72 is provided to actuate the pump rod assembly which is shown encased in the drop pipe 73. At the bottom of the well, a casing pipe 75 is provided to encase a working barrel 76 in the conventional manner. Holes 77 are provided in the casing pipe to allow the infiltration of water. To connect the pump jack 72 with the working barrel 76 located at the bottom of the well, the pump rod segments 80, 81 and 82 are shown consecutively connected by the twisted strap type couplings 84 and 85. Such couplings have previously been described in detail. With a well of 15 curved configuration as is shown in Fig. 6 most of the bending will occur in the pump rod segments which have their cross sections disposed relative to the well curvature in a manner exemplified by the rod segment 81. In other words, with a well curvature such as is shown in Fig. 6, the segments, which are disposed relative to such curvature in the manner of segment 81, will be easily bent to conform the pump rod assembly to the well curvature. On the other hand the segments 80 and 20 82, which are disposed ninety degrees to the segments such as 81, will remain practically unbent when disposed in a well curvature such as is shown in Fig. 6. It should be noted that there is very little clearance between the rod segments and the drop pipe in the direction of the width of the segments. I prefer to make the width dimension of the rod segment about $\frac{1}{16}$ inch less than the inside diameter of the drop pipe. This close fit permits the application of pressure on a down stroke without buckling the rod segments when double acting working barrels are used.

It should be noted that with my inexpensive type of coupling it is economically advantageous to use a greater number of shorter rod segments which necessarily require the use of a greater number of couplings. This feature provides two main advantages. Shorter wooden rod segments can be made from standard mill lumber of standard, readily available planks. This results in a great saving in pump rod segment cost.

Secondly, since the couplings themselves are of a simple inexpensive type, a greater number of such couplings can be used in a well of given depth without incurring excessive coupling expense. Hence it may be seen, that not only does my pump rod assembly provide a flexible installation for curved wells, but it also furnishes a mechanism which will function with a minimum of objectionable noise. By making up a pump rod assembly of a greater number of shorter pump rod segments, as I prefer to do in the present teaching, I find that the assembly of segments will bend to a configuration that more accurately conforms with the configuration of the well curvature. This is true because bending of the assembly to conform with well curvature most readily occurs along those of the segments which have their small cross-sectional dimension subjected to bending by the well curvature. Such a segment is illustrated at 81 in Figure 6. Hence by employing a relatively large number of segments, those of the segments which have their small cross-sectional dimensions disposed favorably for the well curvature will occur at more frequent intervals along the longitudinal extent of the assembly whereby the assembly can bend with a more continuous arc which more accurately conforms with the well curvature. At the same time, by increasing the number of pump rod segments through the use of my novel couplings, I effect a great saving in the cost of pump rod lumber.

While the forms of embodiments of the present invention as herein disclosed constitute preferred forms, it is to be understood that other forms might be adopted, all coming within the scope of the claims which follow.

I claim:

1. A flexible pump rod assembly for curved wells comprising, in combination, a plurality of flexible rod segments of rectangular cross section consecutively disposed end to end, the width of each segment being greater than the thickness thereof, each of said segments having end portions provided with holes, and axes of length, width and thickness with the axis of width of each segment being disposed at substantially ninety degrees to the axis of width of the next adjoining segment, and a coupling comprising a pair of metal straps each of which has a twisted center portion connecting plane end portions which are disposed substantially ninety degrees to each other, with one plane end portion of each strap being lap joined to the end of a segment along the face of such segment corresponding to the axis of width and with the other plane end portion of said strap being lap joined to the end of the next succeeding segment along the face of such segment corresponding to the axis of width, with holes in each of said plane end portions located to register with said holes in the adjoining segment end, and fastening means passing through the holes in said straps and said segment ends for securing same in lap joined relation.

2. A flexible pump rod assembly for curved wells comprising, in combination, a plurality of flexible rod segments of rectangular cross section consecutively disposed end to end, the width of each segment being greater than the thickness thereof, each of said segments having end portions provided with holes, and axes of length, width and thickness with the axis of width of each segment being disposed at substantially ninety degrees to the axis of width of the next adjoining segment, and a coupling comprising a pair of metal straps each of which has a twisted center portion connecting plane end portions which are disposed substantially ninety degrees to each other, with one plane end portion of each strap being lap joined to the end of a segment along the face of such segment corresponding to the axis of width and with the other plane end portion of said strap being lap joined to the end of the next succeeding segment along the face of such segment corresponding to the axis of width, with the plane end portion of each coupling strap provided with protruding bearing portions extending into the segment end joined thereto, with holes in each of said protruding bearing portions located to register with said holes in the adjoining segment end, and fastening means passing through the holes in said straps and said segment ends for securing same in lap joined relation.

3. A flexible pump rod assembly for curved wells comprising, in combination, a plurality of flexible rod segments of rectangular cross section consecutively disposed end to end, the width of each segment being greater than the thickness thereof, each of said segments having axes of length, width and thickness with the axis of width of each segment being disposed at substantially ninety degrees to the axis of width of the next adjoining segment, a coupling comprising metal strap means mounted on each segment end and extending to the end of the next succeeding segment, with said strap means having a twisted center portion connecting plane end portions which are disposed substantially ninety degrees to each other, with one of said plane end portions being lap joined to the end of a segment along the face of such segment corresponding to the axis of width and with the other of said plane end portions being lap joined to the end of the next succeeding segment along the face of such segment corresponding to the axis of width, and means for securing said plane end portions of said coupling to said faces of said segments.

4. A flexible pump rod assembly for curved wells comprising, in combination, a plurality of flexible rod segments of rectangular cross section consecutively disposed end to end, the width of each segment being greater than the thickness thereof, each of said segments having axes

of length, width and thickness with the axis of width of each segment being disposed at substantially ninety degrees to the axis of width of the next adjoining segment, a coupling comprising a pair of metal straps each of which has a twisted center portion connecting plane end portions which are disposed substantially ninety degrees to each other, with the plane end portions of the strap being lap joined to the end of a segment along the face of such segment corresponding to the axis of width and with the other plane end portion of said strap being lap joined to the end of the next succeeding segment along the face

of such segment corresponding to the axis of width, and means for securing said plane end portions of said coupling to said faces of said segments.
